[57] CLAIM

The ornamental design for a travel toothbrush, as shown and described.

DESCRIPTION

FIG. 1 is a top right side perspective view of a travel toothbrush showing my new design;

FIG. 2 is a front end elevational view of the toothbrush shown in FIG. 1;

FIG. 3 is a right side elevational view thereof, the left side being identical thereto;

FIG. 4 is a top plan view thereof; and,

FIG. 5 is a bottom plan view thereof; and,

FIG. 6 is a rear end elevational view thereof.
